AUTOMATIC CONTROL FOR TYPESETTING MACHINES

Karl Nause, Köln-Deutz, Germany

Application February 24, 1959, Serial No. 795,111

Claims priority, application Germany February 25, 1958

4 Claims. (Cl. 199—18)

The present invention is concerned generally with typesetting machines and is more particularly directed to a device for controlling automatically released matrices in typesetting machines which is operated by means of punched tapes.

In previously disclosed devices control tapes used are punched by a perforator such as that disclosed in U.S. Patent 2,059,250. Perforators of the character involved generally comprise a conventional typewriter keyboard, punching means and counting mechanism. The counting mechanism generally includes a counting scale, a unit indicator to indicate the thickness of the matrix being employed, space band indicators and matrix frames with associated counting mechanism. The unit indicator is provided with pointers, the position of which indicating when a punched line is completed whereupon the completed line is justified and cast on the typesetting machine. A typical machine of the character involved is disclosed in U.S. Patent 2,091,286.

The tape utilized in previously disclosed typesetting machines had to be punched to the line width used, depending upon the size of the type required. In such an instance the dimensions are fixed at the time the tapes are punched and thus these tapes are limited to use only for the predetermined line width and size for which they were originally punched. When other line widths and type sizes are involved, the perforator had to be readjusted according to the new dimensions involved.

An object of this invention is to provide a device usable with a punched tape which is perforated according to the text and spacing in a continuous succession and which can be used in automatically operated typesetting machines without taking into consideration dimension changes resulting from the use of different type widths.

Generally in the prior art matrices are positioned one after the other in rows, the number of matrices per row and the size of the type being used determining the width of a line on a typesetting machine. The lines formed are justified by interpositioned space matrices and such space matrices are inserted in a line by manual operation of a "space" key. Hyphen matrices are also positioned in a line being composed by a manually operated "hyphen" key.

When using perforated tape with punches in continuous succession, there often occurs that a line will end in a completed word; however, a hole on the perforated tape after those completing the word will function to cause an unnecessary space matrix to be released. In order to eliminate the unnecessary release of such matrices, the present invention provides means functioning to prevent such release, this means functioning to prevent operation of the corresponding "space" matrix release bar of the machine.

The device of the invention affords the expedient of using previously punched tapes for use with various line widths and letter sizes. The device is specially desirable for use on automatic typesetting machines in rela-

2

tively small printing establishments where there is a limited number of different type sizes and where the cost of a perforator or similar device is prohibitive.

Thus a further object of the invention comprises a device for the release of matrices in a typesetting machine operated automatically by perforated tapes and includes means for operating a cam yoke, and means for selectively preventing operation of the cam yoke and operation of a cam release bar.

10 Other objects and advantages of the invention will become apparent during the course of the following description. In the drawing there is shown one preferred embodiment of the invention.

In the drawing:

15 Fig. 1 is a fragmentary elevational view, with portions shown in section, of a conventional matrix release mechanism, and illustrating means for immobilizing or preventing the operation of a cam actuated cam yoke; and

20 Fig. 2 is a fragmentary plan view of an assembler slide used in the invention.

Referring to the drawing in detail, in Fig. 1 there is shown a mechanism for operating a matrix release bar.

1. This mechanism includes a key lever 2, which may 25 control the "space" or "hyphen" matrix, and is pivoted at its center at 2' and including at one end a key head 3. The key lever 2 will be automatically operated or controlled by a perforated tape in the conventional manner. A vertically disposed dead weight bar 4 includes

30 at one edge parallel to the vertical axis of the bar 4 vertically spaced notches 4', 4''. A trigger bell crank 5 is pivoted on a transverse shaft 5' and includes a lower arm 5'' terminally and pivotally engaged in the uppermost notch 4' of the bar 4. A lower notch 4''

35 of the bar 4 receives the free end 2'' of the key lever 2, therein whereby the lever is disposed in a substantially horizontal position. The end 5'' of the trigger bell crank 5 pivotally supports one end 6 of a keyboard cam yoke 6', the other end 6'' of this being pivotally supported on a transverse pin 6''', and thus the yoke 6' is normally disposed in a substantially horizontal position. The yoke 6' rotatably supports a cam 7 on a transverse pin 7' which is engageable with a transversely disposed, 40 constantly rotating snatch roll 8. The cam 7 includes a radially extending stop 9. The above mentioned structure is conventional.

45 Mounted above the cam yoke 6' is a vertically disposed solenoid including a reciprocable armature 10 and surrounding electromagnet 11. Upward movement of the 50 end 6 of the cam yoke will engage the lower end of the matrix release bar and operate to release a matrix in the conventional manner.

55 Operation of the structure above is as follows:

A perforated tape will automatically move the key lever 2 counter-clockwise about 2' which will result in raising the dead weight bar 4 and accompanying counter-clockwise rotation of the trigger bell crank 5. Movement of the crank in this manner results in pivoting of the yoke 6' clockwise about 6'', permitting engagement

60 between the cam 7 and roller 8. As the cam 7 rotates it will rise due to stop 9 engaging the snatch roll 8 causing the end 6 of the yoke to raise to operate the release bar 1. If the magnet 11 is energized, as will subsequently be described, the yoke 6' will be prevented 65 from moving downwardly and the cam 7 will not engage the roller 8 and thus no matrix will be released at this time.

70 Referring to Fig. 2, there is disclosed an assembled slide which will function to control the energization of the magnet 11 and armature 10 to prevent the release of a matrix as mentioned above. Indicated at 12 is a

3
collector slide which includes electrical contact portions which will be engaged by a contact 13 during its normal or initial position of or with an adjustable spaced contact 14 at its final position toward which it is being moved. Suitable conducting leads L will connect the contacts 13 to the electromagnet 11. Contacts 14 will be connected by leads L' to another electromagnet and matrix release mechanism (not shown). The slide 12 includes a stop or abutment 16, a clapper 17, and a bell 18 engageable by the clapper shortly before the slide reaches its final position during movement. An adjustable abutment member 20 is provided in the path of movement of the abutment 16 and the assembler slide includes a projecting slide finger 19 and releasing lever 21.

Operation of the assembler slide is as follows:

When the assembler slide is in its initial position at the beginning of a sentence, and a perforation on a continuous succession, control tape designating an "interword" space or hyphen occurs on the tape, contact of the slide 12 with the contact 13 occurs and the magnet 11 is energized as in the position shown in Fig. 1 to prevent the release of a space or hyphen matrix. From its initial position, the slide 12 moves automatically toward the contact 14 according to each perforation in the control tape. When the slide engages the contact 14 which has been previously adjusted, this position being shown in Fig. 2, another electromagnet (not shown) will be energized for the purpose mentioned.

In addition to the automatic energization of the magnet 11 to control operation of the yoke 6, the key 3 may be depressed manually if a control tape is not available. The invention contemplates the energization of the magnet 11 by specific combinations of perforations on the control tape so matrices other than those corresponding to spaces, for example, at the beginning and end of lines may be restrained.

One use of the invention embodies the splitting up into syllables of multi-syllable words on a perforated tape where each syllable is separated by a hyphen. The device is arranged so that the perforation designating hyphens would result in holding the equivalent matrices

back by magnetic means. Control or circuit-closing would be effected by the assembler slide.

Where all multi-syllable words are connected by hyphens, the text would have the following appearance, for example: "The neu-tral punched tape will be pro-duced . . .". When the tape is punched in this manner, the provision of "interword" spaces and "hyphens" need no longer be carried out manually. The assembler slide would function to eliminate hyphens at the ends of lines, this operation being prevented by energization by the electromagnet. As a result the transfer of signals or operation to the typesetting machine will be substantially independent of manual operation and the necessity of rigid supervision by the compositor will be reduced and efficiency of operation will be increased.

The construction shown embodies the invention in a preferred form, but it is intended that the disclosure be illustrative rather than definitive, the invention being defined in the appended claims.

20. What is claimed as new is:

1. For use in a perforated tape operated typesetting machine, means for releasing matrices in the machine comprising a cam yoke, a matrix release bar engageable by said cam yoke in response to activation thereof by a signal transmitted by a perforated tape, and selectively operable cam yoke immobilizing means engageable with said cam yoke to prevent said cam yoke from activating said matrix release bar during predetermined increments of an operating tape.

30. 2. The structure of claim 1 in which said last mentioned means comprises an electrically energized device.

3. The structure of claim 2 including an assembler slide operatively connected to said electrically energized device, said assembler slide including spaced contact portions oriented in relation to the beginning and end of a line being composed and operable to transmit current to the electrically energized device in relation to the contact spacing.

4. The structure of claim 3 in which at least one of 40 said contact portions is adjustable relative to said other contact portion.
